UNITED STATES PATENT OFFICE.

WILLIAM C. ANTHONY, OF STREATOR, ILLINOIS, ASSIGNOR TO ANTHONY COMPANY, OF STREATOR, ILLINOIS, A CORPORATION OF ILLINOIS.

BODY SUBDIVISION.

1,425,821.

Specification of Letters Patent. Patented Aug. 15, 1922.

Application filed April 17, 1920. Serial No. 374,557.

To all whom it may concern:

Be it known that I, WILLIAM C. ANTHONY, a citizen of the United States, residing at Streator, in the county of La Salle and State of Illinois, have invented a certain new and useful Improvement in Body Subdivisions, of which the following is a specification.

My invention relates to improvements in dumping bodies of the type adapted for use on vehicles and relates particularly to removable subdividing gates adapted for use with such bodies. One object of my invention is to provide a dumping gate which may be applied to a dumping body and which will serve to subdivide it so that the load of the body may be dumped in two or more parts. Other objects will appear from time to time throughout the specifications and claims.

My invention is illustrated more or less diagrammatically in the accompanying drawings, wherein,

Figure 1 is a side elevation with parts broken away;

Figure 2 is a similar view showing the body in the tipped or dumping position;

Figure 3 is a vertical section on the line 3—3 of Figure 1;

Figure 4 is a detail of the door locking mechanism.

Like parts are designated by like characters throughout.

A is a truck frame suitably supported upon the running gear B. C is a rack mounted on the frame and adapted to cooperate with the toothed cam C¹ which carries the frame C² upon which the body D is mounted. E is a support for the forward end of the body upon which the angular member E¹ is adapted to rest when the body is horizontal. E² is a hook on the member E³ which overlaps the upper surface of the angular member E¹ and so holds it in position. The member E³ is pivoted at E⁴ and provided with the forward extension E⁵ which may be depressed in order to free the body for dumping. F is an eccentrically hung tail gate which is normally held closed by means of the hooks F¹—F¹ which are mounted on the rod F². F³ is a lever on the rod F² and adapted to contact the tire or wheel of the vehicle in the manner shown in Figure 2, to automatically open the gate when the body has reached the necessary inclination. F⁴ is another lever on the rod

F² connected by means of a rod F⁵ to the lever F⁶ which is mounted on the body at F⁷. By means of the lever F⁶ the tail gate may be opened at any time at the will of the operator.

G is a subdividing removable gate eccentrically hung from the rod G¹ which is mounted for rotation on the upper surface of the body in the removable bearings G²—G². H—H are locking levers mounted for rotation on the gate G. They are adapted normally to engage the stops H¹—H¹ on the sides of the body. H²—H² are stops adjacent the stops H¹—H¹ and are adapted to limit the forward motion of the gate G. H³—H³ are chains secured to the levers H—H and the arm H⁴ which is mounted upon the rod G¹. H⁵ is a lever arm mounted upon the rod G¹ and integral with the lever arm H⁶ which carries in its end the counter weight H⁷. H⁸ is a chain secured to the lever arm H⁵ by means of which it may be operated to rotate the rod G¹ and so to move the levers H—H freeing them from engagement with the stops H¹—H¹ and allowing the gate to open and to discharge the material from the body.

I is a prop adapted to support the body in the dumping position after the first part of the load has been discharged.

The use and operation of my invention are as follows:

In handling material in dumping bodies it is frequently desirable to be able to dump only a part of the contents of the body at one time. This is particularly desirable in mixing concrete where, for example, a mechanical mixer is used which cannot take the entire contents of the dumping body at one time. In such a situation it is desirable to dump a fraction of the contents into the mixer and then subsequently to dump the remainder of the load. It may be desirable to dump the load in two parts or in more. For such a use my body is particularly adapted. Upon moving to the dumping position the rear tail gate may be opened automatically or at the will of the operator. As the body assumes the dumping position the prop falls into place and so maintains the body in the dumping position even after the first part of the load has been discharged. Subsequently at the will of the operator another fraction of the load is discharged by means of opening the next gate. This process may be continued until the

body is empty. At that time the prop is removed and the body returns to the horizontal position. As this takes place all of the gates will close automatically.

5 It is often desirable to use a dumping body for a variety of purposes. For some uses it is necessary to dump the entire load as a unit. For other uses it is desirable to subdivide it as above outlined. With these 10 requirements in mind I have designed my body so that the subdividing gates may be readily removable. Thus, in the form illustrated herewith it is only necessary to remove the two bearings G^2 G^2 when the gate 15 may be removed bodily. When this has been done there remains in the body nothing but the two gate stops, and the bottom of the body is entirely clear and unobstructed. This is of particular importance as it is essential 20 in dumping bodies to have a smooth and unobstructed floor. It will be understood of course that I might provide my body with any number of such subdividing single gates.

25 Although I have shown in my drawings an operative structure still many changes, both in form, and relation of parts might be made without departing from the spirit of my invention and I wish, therefore, that 30 my drawings be taken as in a sense dia-grammatic.

I claim—

35 1. A vehicle body having two stops on its inner sides and a door adapted to rest against one of them and having a hole to permit it to pass over the other and a movable lock on the door adapted to pass between the door and such second stop.

40 2. A vehicle body having two stops on its inner sides and a door adapted to rest against one of them and having a hole to permit it to pass over the other and a movable lock on the door adapted to pass between the door and such second stop and to 45 cover said hole and to prevent said stop from passing through.

3. A vehicle body having two stops on its inner sides and a door adapted to rest against one of them and having a hole to permit it to pass over the other and a movable lock on the door adapted to pass between the door and such second stop and to move with a wedge action between the door and such second stop. 50

4. In a dumping vehicle a gate located 55 within said vehicle and intermediate its ends, locking means for gripping said gate by a wedge action, said locking means including pairs of fixed members on the wall of the vehicle body, the opposed faces of 60 said members being at an angle one to the other, and a movable member mounted upon said gate and adapted to contact the inner face of one of said members and to force said gate against the inner face of the other 65 of said members in a wedge action.

5. The combination of a dumping body with a gate within it and intermediate its ends, locking means for holding the gate closed at a point separated from its lower 70 edge within said body, and means for opening said gate, and a counter weight adapted automatically to free said locking means to a position in readiness for permitting the 75 same to lock.

6. In a dumping vehicle a gate and locking means for gripping said gate, said means including a pair of members pivoted thereupon and adapted to engage stops on the side of said vehicle, chains upon the inner ends of said members and a rotary shaft upon said body, said chains secured at one end to said shaft, and means for rotating said shaft in one direction to raise said members to free said gate, and automatic 80 means for rotating said shaft in the reverse direction to lower said member to the position in readiness for locking. 85

Signed at Streator, county of La Salle, and State of Illinois, this 14th day of April, 90 1920.

WM. C. ANTHONY.
